BY
Reincke,
ATTORNEY.

UNITED STATES PATENT OFFICE.

WILLIAM WALKER, OF SUMMIT, NEW JERSEY.

DESIGN FOR AN UMBRELLA AND CANE SUPPORT.

SPECIFICATION forming part of **Design No. 28,264, dated February 8, 1898.**

Application filed December 30, 1897. Serial No. 664,742. Term of patent 7 years.

To all whom it may concern:

Be it known that I, WILLIAM WALKER, a citizen of the United States, residing at Summit, Union county, New Jersey, have invented a certain new and original Design for a Support for Umbrellas, Canes, &c., of which the following is a full, clear, and exact description.

My invention relates to a new and original design for umbrella and cane supports, and the same is shown in perspective in the accompanying drawing.

In said drawing, A is a supporting-base.

The leading features of my design are as follows: B B' are forwardly-projecting arms.

These arms are curved outwardly from base A and away from each other, as at D D'. These parts D D' are then curved outwardly and directed toward each other, as at E E'. These parts E E' do not meet, but terminate in short outward bends F F'.

What I claim is—

The design for an umbrella and cane support substantially as shown and described.

Signed at New York this 7th day of December, 1897.

WILLIAM WALKER.
